UNITED STATES PATENT OFFICE.

HANSON GREGORY, JR., OF BOSTON, MASSACHUSETTS.

ORE-CRUSHER.

SPECIFICATION forming part of Letters Patent No. 558,803, dated April 21, 1896.

Application filed August 8, 1895. Serial No. 558,618. (No model.)

To all whom it may concern:

Be it known that I, HANSON GREGORY, Jr., of Boston, in the county of Suffolk and State of Massachusetts, have invented certain new and useful Improvements in Ore-Crushers, of which the following is a specification.

This invention relates to that class of ore-crushing machines in which a series of rolls located on shafts radiating from a vertical driving-shaft are caused by the rotation of said shaft to travel around in an annular bed or trough which receives the ore to be crushed.

The invention has for its object to provide certain improvements in the form of the rolls and bed and in the means for connecting the rolls with the driving-shaft, whereby the rolls are enabled to act on the ore with a pressure due to centrifugal force as well as to their own weight.

20 The invention consists in the improvements which I will now proceed to describe and claim.

Of the accompanying drawings, forming a part of this specification, Figure 1 represents a top view of an ore-crushing machine embodying my improvements. Fig. 2 represents a section on line 2 2 of Fig. 1. Fig. 3 represents a top plan view of the carriage or carrier hereinafter referred to engaged with the driving-shaft, portions of the carrier being broken away and the shaft being shown in section. Figs. 4, 5, and 6 represent detail views hereinafter referred to.

The same letters and numerals of reference indicate the same parts in all the figures.

35 In the drawings, *a* represents a vertical driving-shaft, which receives motion from a suitable source of power, through mechanism such as that shown in Fig. 2.

b represents a hub, which is affixed to the 40 upper end of the shaft *a* and is provided with radiating guides or ways *b'*, which have vertical flanges *b²* *b³* at their edges, said flanges bearing upon the sides of the boxes *c c* (hereinafter referred to) and causing said boxes to revolve about the shaft. The hub *b* and arms *b'* constitute what I call a "carrier," which is 45 rotated by the shaft *a* and is engaged therewith by means of keys *a'* on said shaft.

Each arm *b'* contains two boxes *c c*, and said 50 boxes are connected by a base-plate or web *c'*, each pair of boxes and their connecting-web constituting a holder or support for a shaft *d*

upon which a crushing-roll *e* is mounted to rotate, there being as many shafts *d* and rolls *e* as there are arms *b'*, three being the number shown in the present case. Each of said holders is hinged or jointed to the hub *b* by means of hinge members formed, respectively, on the hub and on the inner box *c*, and a pivot *f*, connecting said hinge members, the arrangement being such that the boxes *c c* and the shafts *d* journaled therein can oscillate in vertical planes to permit the rolls *e e* to rise and fall.

g represents an annular bed which supports 65 the rolls *e*. Said rolls are provided with cylindrical faces *2* and tapering or conical faces *3*, said faces *3* comprising the outer portions of the rolls. The bed *g* is provided with a horizontal portion *4*, corresponding to the cylindrical portions *2* of the rolls, and with an inclined portion *5*, corresponding to the conical portions *3* of the rolls, so that the rolls conform closely to the bed, as shown clearly in Fig. 2. The rolls *e* are affixed to the shafts 70 *d*, and the latter are journaled to rotate in the boxes *c c*, and are also free to move longitudinally in said boxes, so that when the shaft *a* is rapidly rotated the rolls will be pressed outwardly against the inclined surface *5* of the 75 bed *g* by centrifugal force. Hence in crushing the ore I utilize not only the weight of the rolls, but also the above-described centrifugal action.

I prefer to provide springs *h*, arranged to 85 normally move the shafts *d* and the rolls *e* inwardly to separate the conical portions *3* of the rolls from the inclined portion *5* of the bed when the machine is not in operation, or when the centrifugal force is sufficiently reduced to permit said springs to act in the manner described. As here shown, the springs *h* are of helical form and are interposed between the outer boxes *c* and collars *d'*, affixed to the shafts *d*.

g' and *g²* represent annular curbs located, respectively, at the inner and outer edges of the bed *g*, and co-operating with the latter in forming an annular trough or tank which confines a suitable depth of water above the bed. 95 100

I claim—

1. An ore-crushing machine comprising a circular bed, a driving-shaft surrounded by said bed, boxes or supports connected with

said shaft and revolved thereby, shafts journaled in said boxes and movable longitudinally therein, crushing-rolls mounted on said shafts, said rolls and shafts being movable outwardly by centrifugal force, and springs arranged to press said rolls and shafts inwardly.

2. An ore-crushing machine comprising a circular bed having a substantially horizontal working surface 4 and an inclined working surface 5, a series of rolls each having a cylindrical peripheral portion 2 and a conical peripheral portion 3, and means for moving said rolls upon the bed, said means having provision for the outward movement of the rolls by centrifugal force.

3. An ore-crushing machine comprising a circular bed, a driving-shaft surrounded by said bed, a carrier or driver secured to said

shaft, boxes or supports hinged to said carrier and adapted to swing vertically, radially-arranged shafts journaled in said boxes, and movable longitudinally therein, crushing-rolls mounted on said shafts, and movable outwardly therewith by centrifugal force, and springs arranged to press the shafts and rolls inwardly, the said bed being wider than the rolls to permit movement of the rolls cross-wise of the bed.

In testimony whereof I have signed my name to this specification, in the presence of two subscribing witnesses, this 7th day of August, A. D. 1895.

HANSON GREGORY, JR.
